UNITED STATES PATENT OFFICE.

CHARLES RYSTROM, OF ROCKFORD, ILLINOIS.

DESIGN FOR A HEEL-PLATE.

SPECIFICATION forming part of Design No. 29,908, dated December 27, 1898.

Application filed November 10, 1898. Serial No. 696,108. Term of patent 7 years.

To all whom it may concern:

Be it known that I, CHARLES RYSTROM, a citizen of the United States, residing at Rockford, in the county of Winnebago and State of Illinois, have invented and produced a new and original Design for Heel-Plates for Boots and Shoes, of which the following is a specification, reference being had to the accompanying drawings, forming part thereof.

Figure 1 is a perspective view of a rubber heel-plate, showing my new design. Fig. 2 is a section on dotted line *a*, Fig. 1.

As shown in the drawings, the design con-

sists of the heel-plate in the form of a horseshoe, being thickest at the closed end 1 and 15 tapering to the ends of the branches 2. A groove 3 is formed in one face of the plate and that face is corrugated or roughened.

I claim as my invention—

The design for a heel-plate substantially as 20 shown and described.

CHARLES RYSTROM.
